United States Patent Office

Des. 207,082
Patented Feb. 28, 1967

207,082

AUTOMATIC BEVERAGE DISPENSER CABINET
Eldon S. Miller, 2917 Westbrook Drive,

Fort Wayne, Ind. 46805

Filed Nov. 26, 1965, Ser. No. 88,242

Term of patent 14 years

(Cl. D94—3)

FIG. 1 is a front perspective view of my automatic beverage dispenser cabinet, showing my new design;

FIG. 2 is a perspective view taken from one side thereof;

FIG. 3 is a top plan view thereof; and

FIG. 4 is a rear perspective view thereof.

I claim:

The ornamental design for an automatic beverage dispenser cabinet, as shown and described.
